LOCKING MECHANISM

Reginald Arthur Firman, Weybridge, England,
assignor to Vickers-Armstrongs Limited, London, England

Application June 30, 1948, Serial No. 36,239
In Great Britain October 3, 1947

2 Claims. (Cl. 74—469)

1

This invention has reference to locking mechanism of the kind in which a braced linkage is caused to collapse as the result of a lateral blow from a rotary actuator, the linkage being held in the braced position prior to collapse by a holding member constituting part of the rotary actuator. Such a mechanism forms the subject of United States patent specification Serial No. 764,800, now Patent No. 2,548,053. In this mechanism a rotary armature has two abutments adapted to act laterally on either side of a braced linkage of a toggle mechanism, the collapse of such linkage having the effect of unlocking a releasable attachment to which the mechanism is applied. Normally the armature is unenergised and is then resiliently biased so that one of the abutments acts as a holding member to press the linkage against a stationary abutment and so hold it in the braced position. When the armature is energised electromagnetically it is caused to rotate in opposition to the resilient bias so that the second abutment delivers a lateral blow to the linkage and so causes it to collapse.

Whilst the said known mechanism has been proved capable of withstanding shocks of a very high order without inadvertent release of the locking mechanism it is appreciated that there is a risk of failure in this respect when the device is subjected to certain shocks of greater severity, such as those produced by explosions, or the still more severe conditions relating to shocks of a hammer-blow character, and the object of the present invention is to provide means whereby the safety of the mechanism may be increased to such an extent that it will cater for shocks of this nature.

In a locking mechanism of the kind referred to there is provided, according to the present invention, a damping or shock-absorbing member which is interposed between the holding member and the linkage. This shock-absorbing member may take the form of a pad of resilient material such as felt, india-rubber or leather or may alternatively consist of a wire or other spring. The function of this member is to absorb any shock which might be transmitted from the linkage to the actuator, and which might be of sufficient magnitude to cause the actuator to rotate and collapse the linkage.

It is also desirable to reduce the possibility of lateral shocks being transmitted to the linkage from the casing and for this reason it is important to eliminate any stationary abutment on the casing against which the linkage may be pressed in the braced position. Such an abutment is

2

provided in the mechanism described in United States patent specification Serial No. 764,800/47 for the purpose of preventing the linkage passing the aligned position. When such an abutment is eliminated it is necessary to make the linkage self-aligning so that it can collapse only towards the run-away position of the linkage.

Two embodiments of the invention will now be described with reference to the accompanying 10 drawings as applied to the mechanism described in United States patent specification Serial No. 764,800/47 to which specification reference is made for a complete description of the details of operation.

15 In the drawings:

Fig. 1 shows the mechanism with the linkage in the braced position and including a resilient pad as the shock-absorbing member;

Fig. 2 shows the mechanism of Fig. 1 with the 20 linkage in the collapsed position;

Fig. 3 shows the mechanism in the same position as in Fig. 1 but having the shock-absorbing member constituted by a spring wire bridge;

Fig. 4 is a section on the line IV—IV in Fig. 3; 25 Fig. 5 is a perspective view to an enlarged scale of one-half of a linkage included in Fig. 3; and

Fig. 6 is an exploded view in perspective of the 30 rotary actuator and the linkage.

The mechanism comprises two toggle linkages 30 67, 68 and 70, 71. The link 67 of the primary toggle carries a roller-stop 66 which is forced outwardly from between two opposed and slightly inclined faces 621 and 631 by pressure exerted by these faces when a load is supported by the jaws

35 62, 63. The greater proportion of this thrust is taken by an anchorage 69, but since the toggle is not quite in alignment a small portion of the thrust is taken by the secondary toggle, the link 70 of which is connected to the central pivot of

40 the primary toggle.

The secondary toggle is made self-aligning by the provision of abutting inclined surfaces 21 and 22 on the links 70 and 71 respectively, as seen most clearly in Figs. 5 and 6. The toggle is thus allowed 45 to collapse in only one direction, as seen in Fig. 2. The link 71 is further pivoted to the spindle 72 of a rotary armature 73, being forked to provide two arms 711 and 712, one lying on each side of the armature. The armature is slotted at 23 on each side for the reception of the two arms 711 and 712 the slots being of sufficient width to allow a certain degree of relative angular displacement between the armature and the link 71.

The armature is enclosed in a cylindrical cavity 50 74, the walls of which are provided with four soft

55 74, the walls of which are provided with four soft

iron cores 75 extending for the width of the armature. The armature has a winding 76, the circuit to which passes through contacts 77 cooperating with fixed, spring-pressed contacts 78. When the armature is energised the attraction between the pole pieces 24 and the soft iron cores 75 tends to turn it in a counter-clockwise direction from the position shown in Figs. 1 and 3. This causes the side 25 of the slot 23 to strike the underside of the link 71, causing the toggle to collapse into the position shown in Fig. 2. This movement of the armature separates the contacts 77 and 78 and interrupts the excitation of the armature.

In order to prevent the collapse of the toggle before the armature is excited, the armature is impelled in a clockwise direction as seen in the drawings by a spiral clock spring 26. This urges the side 27 of the slot 23 towards the upper side of the link 71, the pressure being transmitted by way of a shock-absorbing member, which latter takes the form of a resilient pad 28 in the mechanism shown in Figs. 1 and 2 and of a spring wire bridge 29 in the mechanism shown in Fig. 3. In either case the member serves to absorb any shock which may be transmitted from the link 71 to the armature 73. In extreme cases the shock might, without the provision of the shock-absorbing member, be sufficient to cause the armature to rotate into the position shown in Fig. 2, thereby causing the toggle 70, 71 to collapse.

The spring wire bridge 29 shown in Fig. 3 and seen more clearly in Fig. 6 comprises two arms 30 attached to one of the poles 24 and joined by a circular cross-member 31. Under the influence 35 of the spiral spring 26 the cross-member 31 is pressed into contact with the knuckle of the toggle, where it rests in a groove 32 of V-section cut across both links 70 and 71 of the toggle. The groove provides a positive lock so that any 40 incipient movement of the toggle is directly opposed by the shear resistance of the bridge 31, and its formation in V-section in conjunction

with the circular section of the cross-member prevents any back-lash between the sides of the groove and the cross-member. When the armature is energised its rotation operates first to relieve the strain in the bridge and then to remove the latter from the groove 32, preparatory to the impingement of the side 25 of the slot 23 against the underside of the link 71 to collapse the toggle.

What I claim as my invention and desire to

10 secure by Letters Patent is:

1. A tripping mechanism for a releasable attachment of the type described, comprising a toggle linkage, a rotary actuator mounted adjacent the said linkage and adapted upon rotation 15 to initiate collapse of said linkage, a holding member on said actuator adapted normally to restrain said toggle linkage in braced position, means for rotating said actuator, and a bridge-shaped spring having two arms attached to a holding member and a cross member arranged to 20 press downwardly upon the linkage in a direction to oppose collapse thereof, said cross member resting in a groove cut across the linkage.
2. A mechanism according to claim 1, the cross 25 member being of circular cross section and the groove being V-shaped.

REGINALD ARTHUR FIRMAN.
